ELECTRICAL ATTACHMENT PLUG

Filed July 28, 1925

UNITED STATES PATENT OFFICE.

MORRIS PROPP, OF NEW YORK, N. Y.

ELECTRICAL ATTACHMENT PLUG.

Application filed July 28, 1925. Serial No. 46,556.

This invention relates to attachment fittings for electric circuits, and more particularly is directed to an improvement in an attachment fitting to provide a plurality of outlets or receptacles for connecting portable appliances to an electric power source.

The object of the invention is the provision of an improved attachment fitting of the character described constructed of few and simple parts, which is cheap to manufacture, and practical and efficient to a high degree.

Other objects of this invention will in part be obvious and in part hereinafter pointed out.

15 The invention accordingly consists in the features of construction, combinations of elements and arrangement of parts which will be exemplified in the construction hereinafter described and of which the scope of application will be indicated in the following claims.

In the accompanying drawing, in which is shown one of the various possible illustrative embodiments of this invention,

25 Fig. 1 is a front elevational view showing the plug form of the device embodying the invention arranged to connect two portable circuits to a screw plug;

Fig. 2 is a side elevational view of the device shown in Fig. 1;

30 Fig. 3 is a view similar to Fig. 2 showing the side cover member removed to expose the interior construction;

Figs. 4 and 5 are cross-sectional views taken on lines 4—4 in Fig. 2 and lines 5—5 in Fig. 3 respectively;

35 Fig. 6 is a perspective view of a modified form adapted to be attached at the ends of portable conductor wires;

Fig. 7 is a perspective view of a modified 40 form of the plug device constructed with a single cover member; and

Figs. 8 and 9 are cross-sectional views taken on lines 8—8 and lines 9—9 in Fig. 7 respectively.

45 Referring in detail to the drawing, 10 denotes a plug attachment device embodying the invention adapted to be inserted into a baseboard flush receptacle, or a screw plug 11 as shown in Fig. 1. The device 10 may com-

50 prise a body portion 12 formed of insulating material such as porcelain, molded insulation, or the like suitable substance, a current-carrying portion 13, and flat cover members 14. The current-carrying portion 13 may be secured in any suitable manner to said body portion 12 as by means of metallic eyelets 16

which are preferably molded into the body portion as shown in Fig. 5.

The current carrying portion 13 is seen to comprise a pair of terminal blades 17 and 18 extending outwardly from one side of the body portion 12 and a plurality of pairs of spring contacting members 19, 19^a and 20, 20^a of any suitable construction extending into through socket passages 12^a said pairs of contact members being spaced in 90 degree relation in said body portion (see Fig. 2). The terminal blades 17 and 18 are formed with elongated flat base portions, such as the arcuate extensions 17^a and 18^a respectively, and the contact members 19, 19^a, and 20, 20^a are formed with flat extension portions 19^b and 20^b respectively, said extensions 17^a, 18^a and portions 19^b, 20^b being firmly secured to the body portion 12 by means of the eyelet anchors 16. The terminal blades 17 and 18 with their respective corresponding contact members 19, 19^a, 20 and 20^a are thus united into a substantial unitary structure with said contact members extending only partially into the passages 12^a to thus eliminate possible short circuits or injury to persons handling the device.

55 The cover members 14 are retained over the current carrying portion 13 on the opposite sides of the body portion 12, by suitable means such as screw 15 which extends centrally through said body portion as shown in Figs. 2 and 4. Each member 14 is provided with a pair of openings 14^a diametrically positioned to permit the insertion of the blades (not shown) of a plug cap 21 to detachably connect with the spring contacts 19 and 20^a or 19^a and 20.

60 For simplicity and cheapness, each of the contact members 19 and 20^a may preferably be formed with single bent portions 19^b and 20^b respectively, and the members 19^a and 20 with looped portions 19^c and 20^c respectively so as to present smooth receiving contact surfaces for terminal blade inserted through openings 14^a of the cover members 14 (see Fig. 5). If desired, each of said contact members may be provided with protuberances 22 for releasably engaging with an opening such as 17^b in terminal blades 17 as is well understood.

65 In using the invention, the device 10 being assembled as shown in Figs. 1 and 2, is connected to a suitable electric power source 110 through a baseboard flush receptacle or a screw plug in the well understood manner.

A plurality of portable circuits 23 through the plug caps 21 may then be detachably connected to the device 10, one on each side thereof as shown in Fig. 1.

5 In Fig. 6 is shown a modified embodiment of the invention in the form of a fitting 10^a which is adapted to be attached at the ends of portable conductor wires 24. Here the extending terminal blades are omitted and suitable terminal binding posts such as screws 25 are provided on the adjacent ends of the arcuate extensions 17^a and 18^a.

Figs. 7, 8 and 9 show a modified form of the device 10 comprising a body portion 33 having a single cover member 34. The current carrying portion 33 is secured to the body portion 30 on one side thereof by the anchor eyelets 16 and the spring contact members 19, 19^a, 20 and 20^a extend into sockets or passage openings 32^a provided in the body portion 34. Each contact member extends only partially into the opening 34^a up to a guard and guiding ledge 32^b formed at one side of said opening to eliminate possible short circuits or injury to persons handling the fitting, said ledges 34^b serving also to restrict the entrance of said openings to all but cooperatively constructed terminal blades (such as blades 17 and 18) of another detachable fitting, and to direct such blades to the spring contact member as is well understood.

To permit the two-part construction of the modified form of device 10^a described above, the terminal blades 37 and 38 are offset at right angles with respect to the arcuate extensions 37^a and 38^a and slots 32^c are provided to receive the said blades as shown in Fig. 7.

The cover member 34 is retained to the body portion 32 over the current-carrying portion 23 by suitable means such as screw 15, as in the device 10 described above.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

55 Having thus described my invention, I claim as new and desire to secure by Letters Patent:—

1. An attachment plug of the character described comprising a one-piece body portion 60 having a plurality of through-socket openings, and current carrying portions of uniform size and shape carried in spaced relation by said body portion, said current carrying portions including pairs of spring contact members extending wholly within said socket

openings, each of said pairs having its members diametrically positioned with respect to a common axis thru said body portion, said contact members being disposed to receive independent circuits. 70

2. An attachment fitting of the character described comprising a body portion having a plurality of parallelly extending through socket openings, and current-carrying portions secured to the body, said current-carrying portions including pairs of spring contact members extending within said socket openings, there being a single contact member disposed within each opening and similarly shaped terminal connecting pieces each secured to one of each pair of said contacting members, each pair of contacting members being disposed to connect with an independent detachable fitting from the side of said body portion opposite that which connects with another fitting. 75

3. An attachment fitting of the character described comprising a cylindrically-shaped body portion having a plurality of through passages extending parallel to the central axis of said body portion, the passage openings in the base of said body portion being diametrically positioned and uniformly spaced with respect to each other, pairs of spring contact members positioned within said passages, and arcuately-shaped terminal connection pieces secured to one of each pair of said contact members, each pair of contact members being adapted to connect with an independent circuit. 80

4. An attachment fitting of the character described comprising a cylindrically shaped body portion having a plurality of parallel passages extending between the circular shaped bases of said body portion, the passage openings in said bases being diametrically positioned and uniformly spaced, current carrying portions carried by the body portion, said current carrying portion including pairs of spring contact members extending within said passages, each pair of contact members being adapted to connect with an independent circuit, said body portion having at least one circular base formed with a recess in which a current carrying means is positioned, and means retained in said recess for partially covering the current carrying parts to prevent accidental contact. 100

5. An attachment fitting of the character described comprising a body portion having a plurality of pairs of parallelly extending through socket openings, and covering means retained on the opposite sides of said body portion, said means having a pair of openings at each of said sides in alignment with a pair of said socket openings to permit insertion of a pair of terminal blades into each pair of socket openings. 105

In testimony whereof I affix my signature.
MORRIS PROPP.
